EVAPORATION COOLER

Thomas B. Martin, Pacific Palisades, Calif., assignor, by mesne assignments, to William L. Rawn, Jr., Robert J. Barnes, and Dickinson B. Barker, Los Angeles, Calif., as tenants in common

Application February 7, 1955, Serial No. 486,490

6 Claims. (Cl. 261—29)

This invention has to do with evaporation coolers and has, among its objects and advantages, the provision of an evaporative cooler:

(1) Wherein the construction is such that the pad element forms a seal with the outer casing;

(2) Wherein the moving parts are all suspended from a single removable panel, thereby greatly facilitating assembly and repair;

(3) Wherein the driving motor, blower and pump are all mounted to rotate about a single axis, thereby eliminating costly connections and rendering the device extremely compact;

(4) Wherein I provide a novel arrangement for connecting the pump and blower wheel to the motor shaft, thereby eliminating the necessity of a double-shafted motor;

(5) Which incorporates a novel water pump mechanism which is extremely economical to manufacture, efficient, and provides circumferentially spaced outlets from the pump housing to insure effective and properly distributed water flow;

(6) Embodying a novel arrangement for catching any moisture which might accumulate on the louvers as a result of operation;

(7) Embodying a novel arrangement for retaining the water-absorbent pads in proper position, facilitating both initial installation and removal and replacement; and

(8) Wherein I provide novel means for properly distributing the water on the pad element.

Still further subordinate objects and advantages will appear hereinafter.

Without intending thereby to limit the broader scope of my invention as defined by the accompanying claims, I shall now describe the presently preferred embodiment thereof, for which purpose I shall refer to the accompanying drawings wherein

Fig. 1 is a front side elevation with parts broken away and parts shown in section for illustrated purposes;

Fig. 2 is a top plan view with part of the top cover broken away;

Fig. 3 is an enlarged section taken on line 3—3 of Fig. 2;

Fig. 4 is a fragmentary plan view of the water distributing trough;

Fig. 5 is an enlarged section taken on line 5—5 of Fig. 2;

Fig. 6 is an enlarged section taken on line 6—6 of Fig. 5;

Fig. 7 is a side elevation with part broken away;

Fig. 8 is an enlarged section taken on line 8—8 of Fig. 7; and

Fig. 9 is an enlarged sectional view of the pump element.

Referring now to the drawings, the numeral 5 denotes a casing having a rectangular base or bottom portion 6 having a bottom wall 6a and side walls 6b. The base is preferably provided with feet 7. The bottom portion of the base provides a water reservoir 8.

A louvered side air inlet baffle 10 is U-shaped in horizontal section, preferably having vertical louvers 10a and defines the back and ends of the casing. Panel 10 is supported from the base by means of the outturned flanged portion 14 of the panel being secured to the side wall of the base, as by screws 15.

As best shown in Figs. 1, 3 and 7, the plane of the outer surface of the panel 10 is inwardly offset from the plane of the side walls 6b of the base by the flanged portions 14, 14a, so that any moisture which may accumulate on the panel in the form of droplets may fall back into the reservoir after being caught in the collecting chamber provided by the flanged portion 14 which is below the top edge of the base side wall 6b.

A front panel 20 has a rectangular medial opening 20a, said panel being curved at its corners 21 and its ends 22 are turned inwardly to function as abutments for the side edges 24 of the panel 10. The front panel is secured to the front side wall 6b of the base as by screws 25. The top and bottom edge portions 20b and inner edge portion 20c of the front panel are inturned. A louvered panel 23 is secured to panel 20 within opening 20a, the louvers 23a preferably being horizontal.

A rectangular cover or top portion 30 has a top wall 30a and side walls 30b, the latter being secured to the front panel by screws 32 and to upper flanged portion 14a of the side panel 10 by means of screws 36.

A fibrous water-absorbent pad 40 of U-shaped horizontal section is disposed against the inner surface of the side panel 10, being held in such position by spaced vertically disposed bars 42 whose lower ends are hooked at 43 through holes in the bottom flanged portion 14 of panel 10, and whose upper ends 44 are hooked in holes provided in the upper flanged portion 14a of panel 10. The bottom edge portion of the pad depends into the water reservoir and against the bottom wall of the base, while the top edge portion of the pad is turned outwardly adjacent its top edge so that its top edge portion is engaged by the cover 30 to provide a seal therebetween. This greatly facilitates and simplifies the changing of the pad as well as the initial assembly of the device and prevents air from passing around the top edge of the pad.

A water distributing trough 50 is also U-shaped in horizontal section and is V-shaped in cross-section, extending over the outwardly and upwardly disposed top portion 40a of pad 40 and having end closures 50a. The trough also has a series of longitudinally spaced spillways 54 provided by striking a substantially semi-circular portion 54a from the trough, the portion 54a being bent out of the plane of the trough and serving to properly direct the water onto the pad. The corner portions 50a of the trough are pinched or restricted so that water does not pass freely past the corners from one section of the trough to another.

The scroll 56 of the centrifugal blower unit 55 has its discharge end secured to the inturned portions 20c of the front panel as by screws 58, the discharge end of the scroll being thus in communication with the casing outlet defined by the louvers 20a. The scroll is thus mounted in spaced relation to the bottom wall 6a of the base.

The motor 60, which is connected to a suitable electrical source by wires, not shown, is suspended in and concentric with the central opening 61 of the scroll by means of brackets 63 secured at their ends to the top of the scroll by screws 64 and secured to the motor housing by screws 65.

The shaft 70 of the motor depends below the motor and fits in the upper portion of a sleeve 71. The hub 72 of a conventional centrifugal blower wheel 75 is secured on the sleeve by set screw 73 which screw also engages the motor shaft to secure the sleeve thereon. The blower wheel of course discharges air through its

vaned periphery into the scroll. A pump drive shaft 78 has its upper end secured in the lower part of the sleeve as by a set screw 75 and, on the bottom end of shaft 78 I secure, as by a screw 76, a longitudinally channelled impeller blade 80. The blade 80 rotates in a pump housing 82 whose top wall 83 is suspended from the annular neck 84 of the scroll by means of the brackets 81. The shaft 78 loosely extends through a rubber-like bearing 79 disposed in an axial opening in the top wall of the pump housing, the space between the shaft and bearing providing an additional water outlet and also to allow slight lateral play of the shaft.

The top wall of the pump housing has three circumferentially spaced outlet openings 85 each carrying a nipple 86 on each of which nipples I mount a flexible delivery hose 87 (Fig. 9), the discharge ends of the hoses 87 communicating with the water distributing trough 50 at points spaced longitudinally therealong.

The rear side wall of the base 6 has an outwardly bulged or flared portion 90 to provide a spout for filling the reservoir with water.

From the foregoing it will be observed that all the moving parts of the cooler are suspended from the scroll, which in turn is mounted on the front panel, so that by removing the top cover and the front panel, the scroll and all the moving parts may be removed from the casing. To remove the pad and install a new one it is only necessary to unhook the top ends of the rods 42 from the flange 14a and swing them away from the pad to permit the pad to be removed. After a new pad is installed, it is only necessary to rehook the top ends of the rods to the trough. The mounting of the motor, the blower wheel and the pump about the same vertical axis eliminates the necessity of many parts and connections which are necessary in conventional coolers, the motor is always exposed to the moving air stream so that it is kept effectively cool, and the cooler may be made extremely small and compact. Since the louvers 10a are inwardly offset from the side walls of the base, any moisture accumulating on the louvers will, of course, drop back into the reservoir.

In operation the reservoir 8 is filled with water, which is picked up by the pad, in addition to being deposited on the pad by the pump, the motor operates the blower to draw air through the side panel louvers and through the absorbent pad and to discharge it into the scroll which directs it through the front panel outlet.

I claim:

1. In an evaporative cooler, a hollow casing having opposed vertically spaced top and bottom portions, said top portion having a top wall and depending side walls and said bottom portion having a bottom wall and upright side walls defining a water reservoir, a front panel disposed uprightly between said top and bottom portions and having an air outlet, a louvered panel of U-shaped cross-section disposed uprightly between said top and bottom portions and providing an air inlet, means spacing the lower end portion of said louvered panel inwardly from said upright side walls below the plane of the top edge of the latter whereby to provide a water collecting chamber therebetween, a water absorbent pad of U-shaped cross-section disposed uprightly against the inner surface of said louvered panel, power driven means for drawing air into said casing through said pad and discharging it through said outlet and means for pumping water from said reservoir onto said pad.

2. The device of claim 1 which additionally includes means for releasably retaining said pad against the inner surface of said louvered panel comprising a U-shaped rod having a medial portion disposed against the inner sur-

face of said pad, side portions extending transversely through said pad and hooked end portions releasably engaging said louvered panel.

3. The device of claim 1 wherein said last two mentioned means are suspended from said front panel.

4. In an evaporative cooler, a hollow casing having opposed vertically spaced top and bottom portions, said top portion having a top wall and depending side walls and said bottom portion having a bottom wall and upright side walls defining a water reservoir, a front panel disposed uprightly between said top and bottom portions and having an air outlet, a louvered panel of U-shaped cross-section disposed uprightly between said top and bottom portions and providing an air inlet, said louvered panel being inwardly offset from the plane of said side walls of said bottom portion, a water absorbent pad of U-shaped cross-section disposed uprightly against the inner surface of said louvered panel, power driven means for drawing air into said casing through said pad and discharging it through said outlet, said pad having its top marginal portion curved outwardly into sealing engagement with the side wall of said top portion and its bottom marginal portion depending into said reservoir, a water distributing trough of U-shaped plan section disposed against the inner surface of said curved portion of said pad and means for moving water from said reservoir into said trough.

5. In an evaporative cooler, a hollow casing having opposed vertically spaced top and bottom portions, said bottom portion having a bottom wall and side walls defining a water reservoir, an upright front panel between said top and bottom portions and having an air outlet, a louvered panel disposed uprightly between said top and bottom portions and forming an air inlet, the lower end portion of said latter panel being inwardly spaced from the side walls of the bottom portion whereby to provide a water collecting chamber therebetween, a water absorbent pad disposed uprightly against said louvered panel and extending into said reservoir, and power driven means for moving air into said casing through said pad and discharging it through said outlet.

6. In an evaporative cooler, a portable hollow casing having a water reservoir in its bottom, and upright, U-shaped, louvered air inlet panel, an upright air outlet panel, a U-shaped water absorbent pad disposed uprightly against the inner surface of said air inlet panel, a power driven pump communicating with said reservoir, means for moving air inwardly through said air inlet panel and discharging it outwardly through said air outlet panel, and a U-shaped trough having water distributing leg portions, said trough being disposed at the upper portion of said pad in position to deposit water thereon, means permitting only restricted flow between said leg portions and water-passing conduits having their outlet ends in communication with said pump and discharging respectively at their outlet ends into said respective leg portions of said trough.
